FIG. 1 is a front elevation view of a spring for a memory card connector, showing our new design;

FIG. 2 is a bottom plan view thereof;

FIG. 3 is a right side elevation view thereof;

FIG. 4 is a rear elevation view thereof;

FIG. 5 is a top plan view thereof;

FIG. 6 is a left side elevation view thereof;

FIG. 7 is a top, left and front perspective view thereof;

FIG. 8 is a top, right and front perspective view thereof;

FIG. 9 is a top, right and rear perspective view thereof;

FIG. 10 is a bottom, left and front perspective view thereof;

FIG. 11 is a bottom, right and rear perspective view thereof;

FIG. 12 is a top, left and rear perspective view thereof; and,

FIG. 13 is a sectional view thereof, taken along lines 13—13.

The broken lines showing of the environment are for illustrative purposes only, and form no part of the claimed design.
